(57) **CLAIM**

The ornamental design for a universal camera mount, sub-
stantially as shown and described.

DESCRIPTION

FIG. 1 is a perspective view of the back of the universal
camera mount showing the new design in a non-extended
configuration.

FIG. 2 is a perspective front view of a non-extended configura-
tion.

FIG. 3 is a perspective back view of an extended configura-
tion.

FIG. 4 is a perspective front view of an extended configura-
tion.

FIG. 5 is a front view of a non-extended configuration.

FIG. 6 is a side view of a non-extended configuration.

FIG. 7 is a back view of a non-extended configuration.

FIG. 8 is a front view of the extended configuration.

FIG. 9 is a side view of the extended configuration.

FIG. 10 is a back view of the extended configuration; and,

FIG. 11 is a bottom view of the extended configuration.

The broken lines in the drawings depict portions of the uni-
versal camera mount that form no part of the claimed design.

1 Claim, 11 Drawing Sheets
